CONTAINER

Adrian O. Daller, Dennisport, Mass., assignor to
 Daller Carton Co., Inc., New York, N. Y., a
 corporation of New York

Application March 16, 1934, Serial No. 715,866

11 Claims. (Cl. 229—51)

This invention relates to containers, and more specifically to containers having tucking-in flaps.

In general it is an object of the invention to provide a device of the character described, which is simple and economical of construction, which can be expeditiously and conveniently manipulated, and which can be readily manufactured and assembled.

Another object of the invention is to provide a container having a tucking-in flap extending from a hinged cover, which flap did not extend from said cover before said container was first closed or sealed.

Another object is to provide the hinged cover of a container with a gripping flap, which gripping flap was not associated with said cover before the container was closed; to provide such a container with an irregular score line, whereby said score line may be more easily broken; to utilize a portion of a side wall bounded by an irregularity in said score line as a gripping flap for said cover once said container has been opened or unsealed; and to utilize the space left by the removal of said portion to assist in gripping the cover after the container has once been unsealed and reclosed.

Other objects of the invention will in part be obvious and will in part appear hereinafter.

The invention accordingly comprises an article of manufacture possessing the features, properties and the relation of elements which will be exemplified in the article hereinafter described and the scope of the application of which will be indicated in the claims.

For a fuller understanding of the nature and objects of the invention reference should be had to the following detailed description taken in connection with the accompanying drawings, in which:

Fig. 1 is a perspective view of a carton embodying one form of the invention and shown before the original closing, a portion being cut away;

Fig. 2 is a perspective view of the device shown in Fig. 1, but after the original closing;

Fig. 3 is a perspective view of the device shown in Fig. 1 taken after the carton has been first broken open;

Fig. 4 is a perspective view of the device shown in Fig. 1 with various flaps rearranged to act as tucking-in flaps and a gripping flap for temporary closure after the carton has been once broken open;

Fig. 5 is a perspective view of a modification of the device shown in Fig. 1, a portion being cut away;

Fig. 6 is a perspective view, similar to Fig. 4, of the device shown in Fig. 5; and

Figs. 7, 8, 9 and 10 are perspective views of a modification of the device shown in Fig. 1 and are similar respectively to Figs. 1, 2, 3 and 4. 5

In the drawings, 10, 11, 12 and 13 denote, respectively, the successively-adjacent walls of the container, which may be termed the front, side, back and side walls. The folding flaps 15 and 16 extend from the side walls 11 and 13 and may be 10 of sufficient length to at least meet. Cover 14 extends from the back wall 12 across the opening formed by the upper edges of the walls, and may extend as far as the upper edge of the front wall 10. It may be integral with the wall 12 and its 15 material may be such that the cover section 14 may be opened up and down as on a hinge along the top of wall 12. The front edges of the folding sections or flaps 15 and 16 may have score lines or slits 18 and 19, having a component perpendicular to the axis of the hinge of the section 14. A section 20 extends from the front wall 10 and overlies the hinged section 14, and is separated from the front section 10 by a score line 21, which is to be broken when the container is 20 opened. This score line may be dispensed with and indicia supplied indicating that the container is to be broken along the top of the front section 10. A portion of the score line may extend down into the section 10 so as to outline a tab 22' 25 therein.

After the container has been filled, the tabs 15 and 16 may be folded down, their upper surfaces glued and the hinged section 14 pressed against them, whereby the latter is secured to the former. 35 Thereafter the section 20 is folded down upon the hinged cover 14. The portion 22 of the section 20, which is adjacent the front wall 10, is secured to the cover 14 as by an adhesive. The container is then in the condition shown in Fig. 2. 40 To open the container, the score line 21 is broken. The section 20 and tab 22' are gripped together and raised. Those parts of the folding tabs 15 and 16 which are set off by the slits 18 and 19, tend to rise with the cover and as the cover is 45 moved further about its hinge, the tabs 15 and 16 tear beyond the slits 18 and 19 in a direction generally determined by the direction of the slits. Those parts of the tabs 18 and 19 between the slits and the side walls are retained by the side 50 walls and the adhesive between the tabs 15 and 16 and the cover section 14 tend to give, with the result that the central portions of the tabs are torn away and remain with the raised cover, while the end portions of the tabs stay and act as short 55

folding tabs thereafter. It is desirable in certain instances to have the grain of the material of the tabs run in a direction somewhat parallel to the slits 18 and 19 to assist in the tearing of the tabs.

- 5 After the intersecured sections 14 and 20 are raised, the portion 23 of section 20 is folded back on the section 22. If desired, the line of fold may be indicated by a score line 25, the section 23 being adjacent the section 22. The section 20
 10 may also comprise a portion 24 lying beyond the portion 23 and set off therefrom, if desired, by a score line 26. The portion 24 is next folded down parallel to the front wall 10 and the tab 22' may be bent up and inserted through a slit 27 appropriately placed in the section 20. This tab 22' thereafter serves to retain the section 20 in the position described, that is, folded back upon itself. The tab 22' may also be used to assist in opening and shutting the container thereafter.
 15 20 After the carton has once been opened and the section 20 folded back upon itself, the cover may be moved back to closed position and the portion 24 will act as a tucking-in flap and will tend to be held in place against the inner surface 25 of the front wall 10, by the front edges of the folding flaps 15 and 16.

It will be observed that a carton is provided, the various sections of which are in general quite like the usual, simple carton. The carton may be 30 formed and sealed with the ordinary carton-making apparatus. By the peculiar arrangement of the parts, the applicant is enabled to have a tucking-in flap and a gripping tab. Beneath the portions 23 and 24 of section 20 printed matter 35 may be inserted on section 14. This matter may be material which the user does not desire to have available until after the container is ready for opening.

Section 20 which overlies the hinged cover, may 40 be divided into four portions, as shown in Figs. 5 and 6. The fourth portion 28, which lies nearest the hinge of section 14, may be secured to the latter section as by an adhesive and may be separated from the portion 24 adjacent thereto by 45 a score line 29. When it is desired to open the container, the score line 29 is broken at the same time as score line 21, and the portion 28 is left secured to section 14, while the adjacent portion 24 is folded forward, as explained in connection 50 with the device shown in Fig. 1.

The hinged section 14 and overlying section 20 may comprise a portion of a wall of the container. As shown in Figs. 7-10, this is a corner portion. Section 14 may be set off from the rest of that wall by a score line 31, except along its hinge 32. The section 20 may also be set off by a score line 30 from the remainder of the section of which it forms a part. A device so arranged permits the contents of the container, 55 after the little cover has been raised, to be poured out of one corner as out of a spout. This action is facilitated by having the flap 15 cut back diagonally from the corner, although this cut back may be accomplished by a tearing action similar to that described in connection with the device shown in Fig. 1.

Since certain changes may be made in the above article and different embodiments of the invention could be made without departing from the scope thereof, it is intended that all matter contained in the above description or shown in the accompanying drawings shall be interpreted as illustrative and not in a limiting sense.

It is also to be understood that the following 70 75 claims are intended to cover all of the generic

and specific features of the invention herein described, and all statements of the scope of the invention which, as a matter of language, might be said to fall therebetween.

Having described my invention, what I claim as 5 new and desire to secure by Letters Patent, is:

1. In a device of the character described, the combination comprising a hinged cover section and a second section integrally extending from and severable from a third section and secured in part to said cover section and having a free portion lying parallel with and adjacent said cover and adapted to be bent back on itself to serve as a tucking-in flap against said third section. 10

2. In a device of the character described, the combination comprising a hinged cover section and a second section integrally extending from and severable from a third section and secured to said cover section in a plurality of separated portions and having a free portion lying between said separated portions adapted to serve as a tucking-in flap for said cover section. 20

3. In a device of the character described, the combination comprising a hinged cover section and a second section integrally extending from 25 and severable from a third section and secured to said cover section in a plurality of separated portions and having a free portion adapted to serve as a tucking-in flap for said cover section, said free portions lying between said separated portions 30 and being set off by a score line from at least one of said separated portions.

4. In a device of the character described, the combination comprising a hinged cover section, 35 a second section integrally extending from and severable from a third section and secured in part to said cover section and having a free portion lying adjacent to and in a plane substantially parallel with said cover section and adapted to serve as a tucking-in flap for said cover section, 40 by being bent back over a portion of said second section secured to said hinged section, and a score line separating said second and third sections.

5. In a device of the character described, the 45 combination comprising a hinged cover section, a second section integrally extending from and severable from a third section and secured to said cover section and having a free portion lying adjacent to and in a plane substantially parallel 50 with said cover section adapted to serve as a tucking-in flap for said cover section, a score line setting off said second section and a portion of said third section from the remainder of said third section, and a slit in said free portion 55 adapted to receive therethrough said portion when said second section is used as a tucking-in flap whereby thereafter said portion may be used as a gripping flap.

6. In a device of the character described, the 60 combination comprising a hinged cover section and a second section integrally extending from and severable from a third section and adhesively secured to and overlying said cover section and having a free portion also overlying said cover section and adapted to serve as a tucking-in flap for said cover section, said hinged section and said third section forming a part of one wall of said device, said hinged section being set off from the remainder of said wall except along the hinge 70 by a score line, and said second section being set off from any portion of said wall with which it is integral, by a score line.

7. In a device of the character described, the combination comprising a hinged cover section 75

- and a second section integrally extending from and severable from a third section and adhesively secured to and overlying said cover section and having a free portion also overlying said cover 5 section and adapted to serve as a tucking-in flap for said cover section, said hinged section and said third section forming a corner of one wall of said device, said hinged section being set off from the remainder of said wall except along the 10 hinge by a score line and said second section being set off from any portion of said wall with which it is integral by a score line.
8. In a device of the character described, the combination comprising a plurality of closing 15 flaps adapted to occupy substantially all of an opening in said device, a hinged cover section secured to said plurality, lines of weakness in said flaps having a component perpendicular to the axis of the hinge whereby when said cover section is hingedly moved a portion of each of said flaps tends to move with and remain secured to said hinged section while another portion of said flaps tends to be separated from said hinged section, a 20 second section, and a third section secured at least in part to said hinged section and integral with and set off by a score line from said second section, a portion at least of the unsecured part of said third section lying substantially parallel with said hinged section and being adapted to serve as 25 a tucking-in flap.
9. In a device of the character described, the combination comprising a plurality of closing flaps adapted to occupy substantially all of an opening in said device, a hinged cover section secured to said plurality, lines of weakness in said 30
- flaps having a component perpendicular to the axis of the hinge whereby when said cover section is hingedly moved a portion of each of said flaps tends to move with and remain secured to said hinged section while another portion of said flaps tends to be separated from said hinged section, a second section, and a third section secured at least in part to said hinged section and integral with and set off by a score line from said second section, said score line setting off a part 10 of said second section with said third section whereby, when said score line is severed, said part may be grasped with said hinged section to assist in moving said hinged section.
10. In a device of the character described, the combination comprising a hinged cover section and a second section integrally extending from and severable from a third section and overlying and secured in part to said cover section, the unsecured portion of said second section comprising 15 a potential tucking-in flap and being adapted, when said second section is severed from said third section, to be folded back upon a portion of said second section, whereby said tucking-in flap may engage said third section.
11. In a device of the character described, a wall comprising a section hingedly secured to a second wall and a second section overlying and partially secured to said hinged section and integral with and severable from a third wall, the 20 unsecured portion of said second section being adapted, when folded back on a secured portion thereof, to serve as a tucking-in flap against said third wall.

ADRIAN O. DALLER. 35
